MAIN-LINE TERMINAL MEANS FOR
LOGGING GEARSDarel L. Maxfield, Forks, and Albert A. Rue,
Beaver, Wash.; said Maxfield assignor to Oiger
Harry Sandberg, Forks, Wash.

Application August 12, 1949; Serial No. 109,932.

2 Claims. (Cl. 294—74)

1

This present invention relates to the general field of logging cables and most especially to means for engaging the main line of a logging unit.

This invention consists of a new form of terminal fitting for a logging choker and a new use for a ferrule terminal fitting applied to the main or haul-in line of a logging unit. This method of operation is predicated upon having on the end of the main line a ferrule fixture, and to provide each of the chokers used with this equipment with a special fitting adapted for easy and secure engagement, either with the main line itself or with the main line and the end terminal fitting.

In the past there has been produced a large number of terminal fittings for cables, chokers and the like, each having as a purpose the improvement in methods of dragging logs on the ground to a central point. Each of these various units serves to a degree its designed and intended purpose. This present invention is believed to be a distinct forward step in the development of this type of gear. The earlier developments were largely predicated upon experience from areas in which logs of limited size were handled; or were adaptable for use with the old types of logging where excessively long cables were employed. The use of this equipment, where relatively large logs are handled, imposes a great deal of work and hardship upon the using personnel.

In an effort to reduce the cost of logging, with the necessary advancement in log handling equipment, the heavy gear has been increased in size to the point where it is very difficult indeed to handle. Now heavy logs require heavy equipment and in this present invention the equipment has been rearranged, re-designed and new equipment provided, so that when logs are to be hauled from a point somewhat removed from the drums holding the main line, this invention provides that the very minimum of gear is attached to the main line, so that its handling can be easily effected. It will be noted in the drawings that the main line has only one relatively small and light fixture as the end terminal. Co-acting with this arrangement is a particularly arranged engaging means on the end of each of the chokers used with the main or haul-in line. These chokers which have been highly developed and are a subject of many separate patents normally consist of a cable which is passed around one end of the log and has provisions for tightening on the log either by means of an

2

eye splice or in later years a wide variety of hooks, all tending to permit the quicker and more secure tightening of the cable with the least damage to it. This present invention uses the ordinary log securing means of the conventional choker, and the engaging means employed on the other end co-acts with the particular arrangement of the main line to provide security and strength, but at the same time makes for the division of the weight to the point that the equipment is easily handled manually.

The principal object of this present invention is to provide a hauling line terminal and haul-in line engaging means for chokers which so distribute the weight that heavy logs can be handled without any one piece of equipment being burdensome in use.

A further object of this invention is to provide coupling means between a main or hauling line of a logging system and the chokers, which arrangement is simple in construction and use and economical in manufacture.

Further objects, advantages and capabilities will be apparent from the description and disclosure in the drawings, or may be comprehended or are inherent in the device.

In the drawings:

Figure 1 is a perspective view showing the manner of using the equipment which is the subject matter of this specification.

Figure 2 is a perspective view showing the main or hauling line terminal means and one preferred form of the choker coupling means.

Figure 3 is a sectional view taken in the same sense as Figure 2 and as though cut by a cutting plane passing longitudinally through the center of the choker haul-in line engaging means.

Figure 4 is a perspective view showing an alternate form of the choker line engaging means.

Referring more particularly to the disclosure in the drawings, the numeral 10 designates the main or haul-in line. In past years, and still used to a limited extent, these hauling lines were reeled on drums on a centrally located donkey, and the present plan as outlined in this invention can be used very effectively with the older equipment. In fact, it overcomes many disadvantages of the older equipment in the handling of heavy gear.

Present day logging, however, is largely done by powerful track-laying tractors, which employ, normally mounted on a track-laying trailer, some form of boom or yoke. This yoke or boom arrangement places the fair lead member, as 12, at a convenient elevation for use and, as the logs

are pulled up to the trailer, it forms a convenient means for raising the leading end of the logs so that they can be dragged for reasonable distances without abutting stumps or other trees or digging into the ground. This equipment is conventional and used in a variety of forms and of course forms no part of this present invention, except that the present invention is particularly well adapted for use with such equipment.

Secured to the extreme end of the haul-in line 10 is the ferrule terminal member 14. This member is secured in place in a variety of ways, probably the best form being that in which the ends of the cable are fanned out and, either with or without the use of a conical plug, the expanded or fanned out ends of the cable are secured within the ferrule by means of, preferably, zinc, melted and poured into the ferrule so as to fill all the voids, and unite the cable and the ferrule. The ferrule is characterized normally by being round or generally cylindrical and having a pressure receiving flat leading or bearing surface 16. It will be apparent, it is believed, that, with a cable so arranged, the workmen as they carry the cable back to the point where the logs have been cut, have a very minimum of weight to handle. This is a matter of real moment when it is realized that the equipment at best is heavy and the friction of dragging the same any distance is very appreciable.

Adapted for co-action with this terminal ferrule, on the end of the haul-in line, is the haul-in line engaging means or fitting 20 of the choker 22. The preferred form of the choker fitting is shown in Figure 2, in which a key-hole shaped slot is provided having the enlarged portion 24 through which ferrule 14 may be passed, and then a reduced portion 26, which is made of a size to properly and loosely fit the haul-in cable 10, but too small to pass terminal 14. The larger opening portion 24 is within the main body of fitting 20, and the reduced slotted portion 26 is in that portion of fitting 20 that is angularly positioned with respect to the main part of member 20. In the preferred form of attachment 20, it is preferred to employ a recess at 30 adapted to receive a tapered ferrule, as 32, formed on the end of choker cable 22. Bore 30 and the connecting bore 34 are co-axially aligned with the main body portion of fitting 20 and normal to opening 24. This construction is believed to be most fully illustrated in Figure 3 of the drawings.

In Figure 4 there is illustrated an optional or alternate arrangement of the terminal fitting. The form of the ferrule receiving opening 24 and the cable receiving slot 26 is identical with the preferred arrangement; however, an opening 38 is provided having its axis substantially parallel to the axis of opening 24, and adapted to receive a cable which is passed through it and doubled back on itself and secured by splicing thereto by clamps or other suitable means.

Method of operation

In using the method and equipment of this disclosure it is normal to bring the tractor with its supporting yoke Y to a convenient position where a number of logs can be reached. The haul-in line 10 is then carried out manually, generally along the line over which the logs are going to be dragged, and as many of the chokers as are going to be required are then threaded onto the haul-in line 10 at a point adjacent each log. The chokers themselves, with the haul-in

line engaging fittings 20 are of considerable weight but as they are being handled one at a time, they do not present a very serious problem. The next step is to place chokers 22 in hauling position on the various logs L. A strain is then

5 taken on the haul-in line 10 and the choker at the end of the haul-in line becomes taut and a continued movement of the hauling-in line starts to move the one log hooked to the end choker. 10 Then, as the line is hauled in further, successive chokers are picked up and each of the line engaging fittings 20 then comes to rest on the choker fittings that have previously been put under strain. With such an arrangement then, 15 there will be one choker fitting 20 abutting the haul-in line terminal ferrule 14 and each successive fitting 20 will abut the fitting previously engaged by the end of the line. This is a very workable arrangement in that the minimum line load 20 can break loose the logs and get them started in motion. This occurs normally one at a time and might be likened somewhat to a railroad train, particularly a freight train, where it has been found advantageous to start the train by back- 25 ing up slightly and then consecutively starting each car. When the group of logs has been hauled up to the fair-lead 12, the front end of the logs will be raised from the ground and are then thus transported to their loading position.

30 It is believed that it will be clearly apparent from the above description and the disclosure in the drawings that the invention comprehends a novel construction of a main line terminal means for logging.

35 Having thus disclosed the invention, we claim:

1. A choker for logging, comprising: a choker cable; means for attaching said choker cable to a log at one end of said choker cable; engaging means at the other end of said choker cable, for securing said choker cable to a haul-in cable having a ferrule terminal; said engaging means comprising an elongated unitary body of less thickness than width, said body having a main portion having in one end a tapered axial opening and said choker cable having a conical ferrule end positioned in said tapered axial opening, said main portion having at its second end a large opening passing transversely from face to back of said main portion, said body having an angular portion extending diagonally from said second end of said main portion, said angular portion forming a large obtuse angle with said main portion, said angular portion having a narrow slot, of a size to pass only a cable, communicating with said large opening, the faces of said angular portion being flattened, to accommodate such ferrule terminal on a haul-in cable and other choker members.

2. An assembly for attaching a series of choker cables to a haul-in cable, comprising: said haul-in cable having a ferrule secured to its terminal end; each choker cable having a ferrule end and having an engaging member having an elongated unitary body of less thickness than width, said body having a main portion having in one end a tapered axial opening and said ferrule end of its choker cable being positioned in said tapered axial opening, said main portion having at its second end a large opening passing transversely from face to back of said main portion of a size to permit passage of said ferrule on said haul-in cable, said body having an angular portion extending diagonally from said second end of said main portion, said angular portion forming a large obtuse angle with said main portion, said

angular portion having a narrow slot communicating with said large opening and said haul-in cable being positioned therein, said slot being of a size to prevent passage of said ferrule on said haul-in cable, the faces of said angular portion being flattened to accommodate abutting objects such as said ferrule on said haul-in cable and other engaging members.

DAREL L. MAXFIELD.
